UNITED STATES PATENT OFFICE.

CHRISTIAN YAUCH, OF DETROIT, MICHIGAN.

DORMER.

1,103,461.

Specification of Letters Patent. Patented July 14, 1914.

Application filed February 5, 1914. Serial No. 816,696.

To all whom it may concern:

Be it known that I, CHRISTIAN YAUCH, a citizen of the United States, residing at Detroit, county of Wayne, State of Michigan, have invented a certain new and useful Improvement in Dormers, and declare the following to be a full, clear, and exact description of the same, such as will enable others skilled in the art to which it pertains to make 5 and use the same, reference being had to the accompanying drawings, which form a part of this specification.

This invention relates to dormers and has for its object a dormer which may be constructed in the shop and applied to practically any kind of sloping roof without the roof being especially designed for the same.

In the drawings,—Figure 1, is a vertical section through the dormer and through the 10 adjoining roof portions. Fig. 2, is a fragmentary section of the dormer taken on and to the extent of the line A—A of Fig. 1. Fig. 3, is a side elevation of the dormer a part being broken away. Fig. 4, is a front 15 elevation of the dormer. Fig. 5, is a vertical section on the line B—B of Fig. 1. Fig. 6, is a vertical section showing a modified form.

The sloping roof is indicated by the character *a*. The hole is made in the roof and the dormer may be applied to the hole. The sheet metal forming the top *b* of the dormer extends up along and in contact with a roof as at *c* (Fig. 1). It may be nailed to the 20 roof and the slate or other shingles may be laid over this strip. A board *d* is nailed to the roof on the inside at the lower end of the opening. This is surmounted by another board *e* and above this is a window seat *f*. Between these two is a strip of metal *g* 25 which forms the lower frame of the dormer window opening. This strip is beaded at *h* and bent out at *i* to form a groove to receive the sash and the lower frame bar of the dormer window opening. The strip continues down as at *j* to form a water shed over the shingles *k*.

The sides of the dormer-window frame are formed by a strip *l* (Fig. 2) which has a turned-up lip *m* that completes the groove to receive the sash. This strip *l* doubles back on itself at the outside, as shown in Fig. 2, so as to form the outside wall *n* of the dormer. This outside wall continues 50 until it meets the roof and then the metal is turned back to parallel the roof and lie thereagainst. It is secured by nails or other fas-

tening means as shown in Fig. 2. The metal web *n* is doubled at *8* and the doubled portion folded back toward the roof. This 60 forms a retaining step to hold the outside edge flashing *9* in the pocket between the retaining strip *8* and the side wall of the dormer. The flashing *9* serves to make the 65 roof water tight when the shingles join the dormer.

Any kind of a plaster support, but preferably a metal plaster support in the nature of roughened or corrugated metal *p* is inserted in the inside of the dormer at the sides 70 so as to form a carrier for the plaster *o*. Of course this plaster may be omitted if it is not desired, as may also the plaster carrier.

A strip of metal *q* runs from side to side of the dormer at the top of the window 75 opening. It is folded back to form the top frame bar of the dormer window and it also has an extension *r* which completes the groove that receives the top sash bar. Another strip *s* is folded over the top edge of 80 the strip *q* and this strip is attached to the larger inclined metal strip *t*. This inclined strip *t* extends across within the dome of the dormer from side to side. It, therefore, supports the upper frame bar of the dormer 85 window frame. The inclined strip *t* serves as a weather shield to prevent air, rain or snow from entering the room behind the dormer by way of the louver. The louver has 90 metal louver-boards *u*.

The air is drawn through ventilating boxes *v* one on each side of the dormer, just below the dome. These are in positions where they will receive all the air currents that are deflected by the sloping roof and 95 caught against the sides of the dormer. A continuation of this box is formed by the side wall *w* which parallels the outside side wall of the dome. This continuation brings the air currents comparatively high in the 100 dome before they are liberated. A sweep-plate *x* bent in an arc of considerable radius extends from the opening in the roof to the top of the dome so as to deflect the air currents issuing from the passageway *w*. This 105 insures the air currents taking the path shown by the arrows in Fig. 1. The air currents, therefore, are practically eliminated from the interior of the room, yet by suction through the controllable register 10 110 they draw out the foul air and fresh air must needs take the place of the foul air. The register 10 is supported on a horizontal sheet metal ceiling 11 that doubles up at

each of the four sides and is fastened to the side walls of the dormer. The vertical cross strip γ serves as a brace for the part-cylinder sheet of metal forming the top of the dome of the dormer.

The window sash is made of a pair of strips that are bent to form a hollow sash bar practically square in cross-section, but having an inwardly extending lip z , which 10 rests against the window frame when the window is closed, and a lip 1 which serves to hold the glass on the outside. The glass is indicated at 2 . A strip 3 may be screwed or otherwise fastened to the sash and abuts 15 against the glass so as to hold the same in place against the lip 1 . The window is hinged by the hinge 4 to the upper frame bar q ; hence the window may be opened out to the position shown in dotted lines in Fig. 20 1 , or other positions. It is held in any desired position by the notched lever 12 .

A screen 5 is located in the ventilator box v and a screen 6 is stretched from the inclined weather shield t to the top of the 25 louver.

In the drawings I have shown my window frame and dormer-window inclined with the roof, but at a slightly different angle. I prefer this construction as it does 30 not require as much material for the dormer and furnishes a greater amount of light to the room behind the dormer. By opening the dormer-window and the register a complete air line through the dormer is provided. This air current sucks out the foul 35 gases in the room without causing a draft in the room proper. In Fig. 6, a modified form is shown. The register is removed and just a hole left, a second window 7 is used 40 back of the swinging sash. This forms an air chamber. The swinging sash may be left open at any angle without letting air into the room at the rear of the dormer. A flue 13 leads into the dormer and this may 45 be used to suck air from any room in the house by merely connecting it up with proper continuing flues and registers (not shown). At the same time the dormer admits light to the room directly behind. This 50 room may be ventilated by connection with flue 13 .

This dormer is made entirely of sheet metal, practically. It may be made complete in the shop and attached to any roof by 55 merely cutting a hole in the same and fastening the extensions of the walls to the roof adjoining the opening.

The dormer works most advantageously when the register is on a plane with the 60 ceiling of the room behind.

What I claim is:—

1. A dormer, comprising a dome having

a louver at the front, an inclined weather shield inclining upwardly and away from the louver, a dormer-window frame below 65 the dome, side walls reaching backward from the dormer window frame, and a ventilator passage opening at the side of the dormer and below the dome, said ventilator passage leading up into the dome and discharging 70 into the dome where the air currents pass over the weather shield and through the louver to the outside.

2. A dormer, comprising a dome provided with a louver at its front end, a sweep-plate 75 consisting of an arched sheet of metal at the rear of the dome and interiorly thereof, a ventilator box opening below the dome and at the side of the dormer, the said ventilator box having a continuation leading up 80 into the interior of the dome, a weather shield inclined upwardly and away from the louver, a dormer-window frame below the dome; and side walls leading from the dormer window frame backward.

3. A dormer-window, comprising a dome of arched sheet metal having louver boards at the forward end, a sheet metal ventilator 90 passage located below and at one side of the dome, strips of sheet metal bent to form a dormer - window frame, further strips of sheet metal bent and fastened together to form a window sash, hinges for hinging the window sash to the window frame, glass carried in the window sash, and sheet metal 95 side walls leading back from the window frame.

4. A dormer, having in combination a dome, side walls continuing down therefrom, a window frame held by the side walls, and an adjustably opening window in the window frame, said dome being provided with 100 openings to allow the discharge of the air.

5. A dormer-window, having in combination, a dome provided with louver boards, 105 side walls continuing down from said dome, a window frame held by the side walls, and an adjustably opening window in said window frame.

6. A dormer, having in combination, a 110 dome provided with louver boards, a flue leading into said dome, side walls continuing down from said dome, a window frame held by said side walls, an adjustably opening window supported by the window frame, 115 and a second window behind the adjustably opening window for closing the chamber formed by the dormer.

In testimony whereof, I sign this specification in the presence of two witnesses.

CHRISTIAN YAUCH.
